UNITED STATES PATENT OFFICE

JOSEPH C. LEWIS, OF MINERVA, OHIO, ASSIGNOR TO CHARLES W. KEPLINGER, RECEIVER OF THE AMERICAN ELECTRIC SWITCH CORPORATION, OF MINERVA, OHIO, A CORPORATION OF DELAWARE

SWITCH AND FUSE BOX

Application filed May 2, 1927. Serial No. 188,168.

The invention relates to entrance boxes such as are ordinarily provided in residences or other buildings between the incoming supply lines and the meter.

5 The object of the invention is to provide a safety box so arranged that access to the fuse plugs can be had only when the switch is in the open position, the fuse plugs being covered by a door which is held in locked position when the switch is closed, means being provided to prevent closing of the door of the box when the switch is in closed position unless the cover to the fuse plugs is locked, and to prevent moving the switch to the "on" position when it is desired to cut off the electric service.

An embodiment of the invention is illustrated in the accompanying drawings, in which

20 Figure 1 is an elevation of the improved box with the door opened, showing the switch in closed position;

Fig. 2, a perspective view of the box, showing the door in closed position, the switch 25 being shown in the "on" position and the cover to the fuse plugs in locked position, parts of said cover being broken away for the purpose of illustration;

Fig. 3, a sectional view through the box 30 showing the parts in the same position as shown in Fig. 2;

Fig. 4, a similar view, showing the switch in the open position and the fuse plug cover locked, this being the position the parts 35 assume when the electric service is cut off to the house, and

Fig. 5, a sectional view through the box, showing the switch in the open position and the fuse plug cover raised to permit access to 40 the fuse plugs.

Similar numerals refer to similar parts throughout the drawings.

The box 1 is preferably made of sheet metal of any usual design and provided with the 45 customary door 2 hinged to one side of the box as at 3 and provided at its other side with the pivoted catch 4 having a perforate ear 5 arranged to be located through the slot 6 formed in the perforated lug 7 upon the side wall of the box which is adapted to pro-

trude through the slot 8 in the door. The usual seal may be located through the apertures 9 in the catch 4 and lug 7 to seal the box in the customary manner.

An insulation block 10 may be fixed upon the bottom of the interior of the box 1, the switch being mounted thereon. This switch 55 may comprise the blades 11 pivoted as at 12 and adapted to contact with the jaws 13 also mounted upon the block 10 and provided with the binding posts 14.

The switch blades 11 may be connected together as by the insulation bar 15 provided with a hook 16 engaging the crank bar 17, the ends of which are journaled through the 60 side walls of the box, one end being provided with the angular handle lever 18.

This lever may extend through a slot 19 in the guide plate 20, fixed to the outside of the box and provided with the indicating 70 legends "on" and "off" at opposite ends of the slot.

The fuse plugs 21 are carried in sockets 22 formed in the porcelain block 23 which may be supported above the base block 10 as by 75 the legs 24.

This fuse block is so positioned that the fuse plugs will be displayed through the opening 25 in the door 2 when the door is closed. Binding posts 26 are provided upon 80 the base block for the connection of wires.

A cover 27 is hinged as at 28 upon the door 2 and arranged to normally cover the fuse plugs 21 in order to prevent access thereto. For the purpose of limiting the opening 85 movement of the cover 27, a stop arm 29 is fixed thereto and extended through an enlarged portion 30 in the slot 31 provided in the door, having its free end inturned as at 32 to engage the under side of the door 2 90 to limit the opening movement of the cover as shown in Fig. 5.

The cover 27 is preferably provided with the rim flange 33 having a lip 34 at its free or swinging edge to permit the finger to be placed thereunder for opening the cover.

A locking plate 35 is slidably mounted upon the inside of the door near the swinging edge thereof. This plate may be provided with the elongated slots 36 engaged by 95

the bolts 37 upon the door and is provided with the angular lip 38 extending through the slot 31 and arranged to be slidably engaged over the flange 33 of the cover 27 when the cover is in closed position.

5 The locking plate 35 is provided with a depending flange 39 having the inclined edges 40 and 41 at opposite ends, and provided with the notch 42 near the edge 40, and adapted to engage the crank bar 17.

10 Thus as the handle 18 of the crank bar is operated to close the switch, it is thrown to the "on" position as shown in Figs. 1, 2 and 3, the locking plate 35 is slidably moved into the position shown in said figures, the angular lip 38 engaging over the rim flange 33 of the cover 27, holding said cover locked in closed position and preventing access to the enclosed fuse plugs 21.

15 In order to open the cover 27 to reach the fuse plugs, it is necessary to throw the handle 18 into the "off" position, opening the switch and sliding the locking plate 35 into the position shown in Fig. 5, moving the lip 38 out of engagement with the rim flange 33 of the cover when the cover may be raised as shown in said figure. Thus access can be had to the fuse plugs only when the switch is open, preventing a person from accidentally receiving an electric shock by touching the fuse plugs 20 when the current is on.

25 When the power company desires to shut off the service, it is only necessary to open the door 2, with the parts in the position shown in Figs. 2 and 3, then throw the switch to the "off" position and close the door. The crank bar 17 will thus contact with the edge 40 of the flange upon the sliding locking plate, preventing movement of the handle 18 toward the "on" position holding the switch in open position and the cover 27 locked in closed position.

30 It will, of course, be understood that the catch 4 will be moved into the locked position as shown in Fig. 2 and the usual seal of the company placed through the apertures 9 in the catch 4 and ear 7.

35 It will be seen that in the event the door 2 is opened with the locking plate in the position shown in Fig. 5, should the switch be moved to the "on" position, the door cannot be closed as the lower or inner edge of the flange 39 will contact with the crank bar 17 and prevent closure of the door, making it necessary to first throw the switch to the "off" position before the door may be closed.

40 Should the cover 27 be opened as shown in Fig. 5, it will be seen that the switch cannot be thrown to the "on" position, as the angular lip 38 will contact with the stop arm 29, preventing movement of the switch handle 18, and locking the switch in open position.

45 From the above it will be obvious that it is impossible to have the switch in closed posi-

tion and the cover 27 unlocked at the same time, thus permitting access to the fuse plugs only when the current is turned off and making the switch box absolutely safe and fool proof.

70

I claim:—

1. A switch and fuse box provided with a door, a switch within the box, a fuse plug within the box, a cover hingedly mounted on the door and arranged to normally prevent access to the fuse plug, means for locking said cover, and means preventing the closing of the door when the switch is closed and the cover unlocked.

15 2. A switch and fuse box, a switch within the box, a fuse plug within the box, a cover having a peripheral rim flange and arranged to normally prevent access to the fuse plug, and a sliding locking plate within the box operatively associated with the switch and 85 having a lip extending outside of the box and arranged to slidably engage the rim flange of the cover.

3. A switch and fuse box, a switch within the box, a fuse plug within the box, a cover 90 having a peripheral rim flange and arranged to normally prevent access to the fuse plug, a sliding locking plate within the box having a notch engaged by the switch, and a lip upon the locking plate extending outside of the 95 box and arranged to slidably engage the rim flange of the cover.

4. A switch and fuse box, a switch within the box, a fuse plug within the box, a cover arranged to normally prevent access to the fuse plug, an arm upon said cover, and a lock for the cover operatively associated with the switch, said arm arranged to prevent movement of the lock when the cover is open.

5. A switch and fuse box, a switch within 105 the box operating means for the switch, a fuse plug within the box, a cover arranged to normally prevent access to the fuse plug, an arm upon the cover, a locking plate operatively associated with the switch and a lip 110 upon the locking plate arranged to engage the cover and to contact with the arm to prevent movement of the locking plate and closing of the switch when the cover is open.

115 In testimony that I claim the above, I have hereunto subscribed my name.

JOSEPH C. LEWIS.
